Filed May 12, 1967, Ser. No. 7,098

Term of patent 14 years

(Cl. D81—4)

FIG. 1 is a perspective view showing front and one side of a cooking stove embodying our new design.

FIG. 2 is an elevational view of the side which is not visible in FIG. 1.

FIG. 3 is a top plan view of the stove shown in FIGS. 1 and 2.

FIG. 4 is a front elevational view of a modified form thereof.

The back of the stove of FIG. 1 and the back and sides of the stove shown in FIG. 4 are plain.

The dominant feature of our invention resides in the portions shown in full lines.

What we claim is:

The ornamental design for a cooking stove, as shown and described.
